Inventor:

William B. Soumeilian

UNITED STATES PATENT OFFICE.

WM. B. SOUMEILLIAN, OF PHILADELPHIA, PENNSYLVANIA.

ATTACHMENT FOR THE LEGS OF BILLIARD-TABLES.

Specification forming part of Letters Patent No. 58,313, dated September 25, 1866.

To all whom it may concern:

Be it known that I, WILLIAM B. SOUMEILLIAN, of the city of Philadelphia, in the State of Pennsylvania, have invented new and useful Improvements in Elevators; and I do hereby declare that the following is a full, clear, and exact description of the same, reference being had to the accompanying drawings, making a part of this specification, in which—

Figure 1 represents a section cut through the base-screw, plate-nut, and washer. Fig. 2 shows an under-side view of the supporting base. Fig. 3 shows a hook-lever or wrench for turning the plate-nut. Fig. 4 is a view of a double-prong wrench and handle for the same purpose.

The object of my invention is to support, elevate, and level up billiard-tables, platforms, or other heavy articles that require nice adjustments, which may be done in the most perfect and easy manner by the use of my improved elevator.

My invention consists in a broad, circular metallic base, having a hollow center-pillar, on which is a substantial screw-thread, to which is fitted a plate-nut, with one or more square notches or recesses in its edge to receive a hook-lever or a single or double prong wrench, and a friction-plate above it; also, in having a recess under the bottom of the base, into which a disk of vulcanized india-rubber is secured, for the purposes hereinafter described.

To enable others skilled in the art to make and use my invention, I will describe it more fully, referring to the drawings, and to the letters marked thereon.

The base A may be made of cast-brass or

other suitable metal, in the bottom of which is a recess in which I secure a ring of sheet vulcanized rubber, B, to form the step or bearing on the floor. This prevents any noise or jar, and forms friction enough to hold it in its place and prevent it from turning as the plate-nut C is being turned up or down on the screw a of the hollow pillow D, the plate-nut C being of considerable dimensions, so as to have a substantial bearing on the friction-plate E, which is placed between it and the table-leg, or the article it is placed under, for the purpose of elevating or leveling up.

In the periphery of the plate-nut C there may be one or more notches, e, into which the nib or square hook f of the wrench F is inserted to raise or lower the nut C, for the purpose of leveling up billiard-tables, or elevating and adjusting anything to a nicety.

Having thus described my invention, what I claim as new, and desire to secure by Letters Patent, is—

1. The combination of the vulcanized india-rubber or other equivalent substance for a step, with a metallic base, hollow-screw pillar, plate-nut, and friction-disk, substantially as and for the purposes herein set forth.

2. In combination with the device above described, the double-armed nib-wrench or hand-lever for operating the same, in the manner and for the purposes specified.

In testimony whereof I hereunto set my hand on this 28th day of August, 1866.

WILLIAM B. SOUMEILLIAN.
